UNITED STATES PATENT OFFICE.

JOSEPH A. MUMFORD, OF HANTSPOST, NOVA SCOTIA, CANADA.

STEAM-BOILER.

SPECIFICATION forming part of Letters Patent No. 350,440, dated October 5, 1886.

Application filed July 24, 1886. Serial No. 208,980. (No model.) Patented in Canada May 6, 1886, No. 21,989.

To all whom it may concern:

Be it known that I, JOSEPH A. MUMFORD, of Hantsport, Nova Scotia, Canada, have invented certain new and useful Improvements in 5 Steam-Boilers; and I do hereby declare the following to be a full, clear, and exact description of the same, reference being had to the accompanying drawings, forming a part of this specification, and to the figures and letters of reference marked thereon.

My invention relates to improvements in steam boilers or generators, and it has for its object to provide a generator that is simple in its construction, can be manufactured cheaply, 15 is not liable to deteriorate by constant use, as others of its class, and one which possesses other advantages that will be apparent to those skilled in the art; and to these ends it consists in certain novel details of construction and combinations of parts, hereinafter described.

In the drawings; Figure 1 is a side elevation of a boiler constructed in accordance with my invention; Fig. 2, a vertical sectional view of 25 the same.

Similar letters of reference in the several figures indicate the same parts.

A represents the shell of the boiler, consisting of the cylindrical casing, constructed 30 in any suitable manner and preferably secured to its base in an inclined position by reason of a pillow-block, a, secured under its rear end, as shown. At the forward end of this boiler is the fire-box or combustion-chamber B, constructed, as shown, of tapering form, with its smaller end toward the rear end of the furnace. The smaller end is closed by the flue-plate C, in which the ends of the tubular flues D are secured in the usual way, their rear ends 35 being secured to the sheet E, also in the usual manner. The forward end of this tapering fire-chamber is secured to the end of the boiler-casing preferably by rivets, as shown, and the taper is so arranged relative to the sides of 40 the casing or shell that the lower wall of the chamber B is parallel with the under side of the casing, while its upper side is approximately horizontal, and as the shell, as described, is inclined, the two casings will 45 diverge toward the rear of the boiler, as will be readily understood.

To the front end of the boiler, and secured

to the fire-chamber and main casing, is a front plate or casting, F, having in it the feed or ash-pit doors b and c, respectively. The face 55 of this plate is somewhat inclined, so as to permit readier access to be had to the doors in order to insert fuel or remove ashes, and to the plate between the doors is secured the end of the grate G, the rear end being supported 60 by the sides of the fire-chamber a short distance from the bottom, as shown.

A suitable damper, d, is provided in the ash-pit door to admit air beneath the grate for the 65 draft.

At the rear end of the boiler-shell is provided a casting or plate, H, projecting nearly vertical from the bottom of the boiler-casing and providing a smoke-box, and it is to the upper side of this that the smoke stack of the 70 boiler is to be secured.

An ordinary steam-dome, I, is provided at the rear end of the boiler proper, from which the driest steam can be taken to run the engine, or for whatever purpose it may be desired, and at the lowest point of the boiler beneath the ash-pit a blow-off pipe or cock, J, is provided to remove the sediment or accumulations within the boiler.

The tubular flues of the boiler, it will be 80 noted, are horizontal and at an angle to the plane of the boiler, and also that the water-level (indicated by the dotted lines in the drawings) is above these flues, and also above the top of the fire chamber, thus keeping the 85 latter covered at all times with water, and not permitting any sediment to collect upon it, or the metal to be rendered dry by the water receding from it and burned through in a short time by the heat of the fire in the furnace. 90 The portion of the boiler below the ash-pit is also at all times filled with water, and the heat of the furnace, not being as great at this point, will not drive out the water by the rapid generation of steam.

The entire ash-pit and fire-chamber being 95 surrounded by the water in the boiler, it follows that no heat generated by the combustion of the fuel will be lost by the radiation downward from the grate, as will be the case where an ordinary form of grate is employed.

All the sediment that might be formed in the boiler will of course fall to the lowest point—that is, below the ash-pit—and it can

readily be blown out through the blow-off cock J, as will be readily understood.

The whole device is very simple in construction, consists of few parts, and they are of such form that if it should become necessary they could readily be removed and new parts substituted. An inclined boiler having a low portion from which sediment can be blown, when desired, is provided, without the liability of having the ends or any portion of the flue-tubes become dry and burned through, or of having the water forced out from around the fire-chamber and a like result ensue.

It will of course be understood that I do not wish to confine myself to the details of construction shown, as others, their equivalents, might be employed with equally good effects.

I claim as my invention—

1. The combination, with the boiler casing, inclined as shown, of the tapering fire-chamber and the horizontal tubular flues communicating therewith, substantially as described.

2. The combination, with the boiler casing, inclined as shown, of the fire-chamber, the horizontal tubular flues communicating therewith, and the blow-off cock located at the lowest point of the boiler, substantially as described.

3. The combination, with the boiler-casing,

inclined as shown, of the tapering fire-chamber, the horizontal tubular flues communicating therewith, the front plate or casting having the fuel and ash doors therein, and the horizontal fuel-support or grate in the tapering fire-chamber, its forward end being supported by the front plate or casting, substantially as described.

4. The combination, with the boiler-casing, inclined as shown, of the fire-chamber secured within the same, having its upper side substantially horizontal, and its lower side inclined and substantially parallel with the wall of the boiler, and the horizontal tubular flues communicating with the fire-chamber, substantially as described.

5. The combination, with the boiler-casing, inclined as shown, of the fire chamber secured within the same, having its upper side substantially horizontal, and its lower side inclined and substantially parallel with the wall of the boiler, the horizontal tubular flues communicating with the fire-chamber, and the blow-off cock located at the lowest point of the boiler, substantially as described.

JOSEPH A. MUMFORD.
